UNITED STATES PATENT OFFICE.

HARRY VASS, OF SUMMIT, NEW JERSEY.

AEROPLANE-PROPELLER.

1,276,455.

Specification of Letters Patent. Patented Aug. 20, 1918.

Application filed October 11, 1917. Serial No. 195,968.

To all whom it may concern:

Be it known that I, HARRY VASS, a citizen of the United States, residing at Summit, in the county of Union and State of New Jersey, have invented certain new and useful Improvements in Aeroplane-Propellers, of which the following is a specification.

This invention has relation to certain new and useful improvements in flying machines and relates more particularly to propellers.

The primary object of the invention resides in the provision of an aeroplane propeller and which may be employed driving the flying machine forwardly or rearwardly or elevating or lowering the machine without changing the direction of the rotation of the propeller.

Another object of the invention resides in the provision of an aeroplane propeller of the above stated character which will be of simple construction and operation and which may be employed in various types of flying machines.

A further object of the invention resides in the provision of a propeller of the above stated character in which will be included a plurality of propeller blades and cam mechanism for changing the adjustments of the blades and thereby causing a different action 30 of the same during operation of the propeller.

A further object of the invention resides in the provision of a propeller of the above stated character in which the blades rotate around the cam member and continually change their positions with respect to the propeller shaft and while rotating around the cam member, the position of the cam member determines the influence of the propeller blades upon the direction of the movement of the flying machine.

A still further object of the invention resides in the provision of a propeller of the above stated character which may be readily assembled and which will be constructed in such manner which should the parts become worn or damaged they may be readily replaced without the necessity of substituting a new propeller.

With these and other objects in view, as will be apparent as the description proceeds, the invention resides in the novel combination and arrangement of coöperating ele-

ments as more specifically set forth herein-after, pointed out in the appended claims as 55 shown in the accompanying drawings.

In the drawings forming a part of this application, and in which similar reference characters designate corresponding parts throughout the several views:—

Figure 1, is a longitudinal section through the propeller.

Fig. 2, is a transverse vertical section on the plane of line 2—2 of Fig. 1, looking in the direction indicated by the arrows.

Fig. 3, is a view similar to Fig. 2, showing the propeller blades and the cam member adjusted for employing the propeller to force the flying machines upwardly.

Fig. 4, is a view similar to Fig. 3, showing 70 the blades and cam mechanism positioned to cause the propeller to drive the machine rearwardly.

Fig. 5, is a view similar to Fig. 4, showing 75 the blades and cam mechanism positioned to cause the propeller to force the machine downwardly.

Fig. 6, is a detail plan of one of the blades, partially in section.

Fig. 7, is a transverse detail section 80 through the blade, substantially on the plane of the line 7—7 of Fig. 6.

Fig. 8, is a detail view, showing the construction of one end of the rotary propeller frame.

Fig. 9, is a detail view of the opposite end, showing manner in which the frame is keyed to the rotary shaft.

Fig. 10, is a detail section through the cam disk and the parts upon which the cam disk 90 is mounted, said view being substantially on the plane of line 10—10 of Fig. 1.

Fig. 11, is a sectional view through the parts shown in Fig. 10 and at a right angle to the same, one of the propeller blade guiding clips being shown in position within a peripheral groove of the cam disk.

Fig. 12, is a detail elevation of one of the clips removed.

Fig. 13 is a transverse section through the 100 same.

Referring more in detail to the drawings, 1 designates the shaft which has a gear wheel 2 mounted upon one end to receive power from an engine or some other source, 105 as may be desired.

In constructing the propeller I am employing a pair of rectangular frame members 3 which are extended at right angles with one another with their end members 5 crossed centrally in the same plates, suitable openings being provided in the crossed ends of the frames to accommodate the shaft 1, so that the propeller may extend longitudinally of the same. Each end of the frame 10 formed by the crossed frame members 3 is provided with an apertured plate or collar 4 and one end of the frame is keyed to the shaft 1, as shown at 5. A sleeve 6 extends through the other apertured plate or collar 4 through the frame stopping short of the opposite or first mentioned end thereof. This sleeve is loosely mounted upon the propeller shaft 1 and has a wheel 7 or the like mounted upon its extended end for the purpose of rotating the sleeve 6 when it is desired to adjust the propeller blades and cam mechanism, as will be later more clearly understood.

It will be understood that the propeller shaft 1 is mounted in any suitable manner 25 in the frame work of the flying machine in which this propeller is incorporated. A cam disk 8 is mounted eccentrically upon the sleeve 6 and keyed to the same, as shown at 9. This cam disk 8 is provided with a 30 peripheral circumferential dove-tail groove 10, the purpose of which will presently appear.

This propeller includes 4 separate but 35 operating blades 11 which are equally provided with trunnions 12 projecting centrally from their opposite ends to form bearings or supports for the blades. Each blade 11 is positioned in one-half of one of the 40 frame members 3 and the trunnions 12 thereof are rotatably mounted in the ends of said frame members 3, as clearly shown in the drawings. Each blade 11 is composed of a 45 rectangular frame 13 with a suitable material 14 stretched around the same and secured thereto in the usual manner, each blade resembling a balancing plane of a flying machine. By mounting each blade in one-half of one of the frame members 3, the blades 50 are arranged at equal distances around the cam disk 8. Each blade is caused to make one-half a revolution within the half of the frame member by which the blade is carried, upon blade revolution of the frame member 55 around the stationary cam disk 8. In order to cause this gradual changing of the angle of the blade with respect to the half of the frame member, I have provided a guiding clip 15 which is of substantially U-shaped 60 form with the free ends 16 of its downwardly extended arms turned toward one another for engagement over the longitudinal edges of a continuous track member 17 surrounding the central portion of the blade

11 and secured to the latter by suitable spacing members 18, as shown in the drawings. Each guiding clip 15 is mounted upon the periphery of the cam disk 8 by a supporting pin 19 having a beveled or flared head 20 riding in the dove-tail peripheral circumferential groove 10 of said cam disk 8.

From the foregoing, it will be understood that when the propeller is operating in the position shown in Fig. 2, the machine will be forced forwardly, each of the blades traveling around the cam member 8 as shown in this view. When the cam member 8 is turned to the position shown in Fig. 3, however, the blades, in passing around the same will tend to force the machine upwardly. When the cam member 8 is in the position shown in Fig. 4, the blades will act to force the machine rearwardly as they pass around the cam member 8 in the manner indicated by this view. When the cam member 8 is moved to the position shown in Fig. 5, however, the blades in passing around the same will serve to force the machine downwardly, owing to the changing of the position of the blades as they pass around the cam member. It will be noted that the cam member 8 is only given a quarter turn to change it from one position to another. It is also noted that the propeller may be placed at any position in the machine. Furthermore this propeller is adapted for use on ships either at the bow or stern or amidships, the changes in the detailed construction necessary to adapt the propeller for this use being considered clearly within the scope of the present invention. It is also to be borne in mind that many minor changes in the details of the construction may be resorted to when placing this invention in practice when departing from the spirit of the invention or the scope of the appended claims.

I claim:

1. A propeller comprising a shaft, a frame rotatable with said shaft, a plurality of propeller blades rotatably mounted in said frame, a track member carried by each of said blades, a cam supported by said shaft, and connections between said cam and blade permitting the angles of the blade to be changed by adjusting the cam relative to the shaft.

2. A propeller comprising a shaft, a frame keyed to said shaft and rotatable therewith, a plurality of propeller blades mounted in said frame, a track member carried by each of said blades, a cam supported by said shaft and provided with a peripheral groove, and a plurality of clips movable in said groove, each of said clips being engageable with the track member of one of said blades.

3. A propeller comprising a cam provided with a peripheral groove, a plurality of spaced propeller blades mounted to revolve

about the periphery of said cam, an endless track member carried by each of said blades, and entirely surrounding the same, clips movable in the groove in said cam member and engageable with said track member, each of said clips including a head portion mounted for sliding movement in said groove and a plate portion having its opposite ends

bent to extend around one of said track members.

In testimony whereof I affix my signature in presence of two witnesses.

HARRY VASS.
